Inventor
Joseph Fisher,
By his Attorney, Chas. H. Fowler

UNITED STATES PATENT OFFICE.

JOSEPH FISHER, OF ATTLEBOROUGH, MASSACHUSETTS.

WEATHER-STRIP.

SPECIFICATION forming part of Letters Patent No. 320,120, dated June 16, 1885.

Application filed April 30, 1885. (No model.)

To all whom it may concern:

Be it known that I, JOSEPH FISHER, a citizen of the United States, residing at Attleborough, in the county of Bristol and State 5 of Massachusetts, have invented certain new and useful Improvements in Weather-Strips; and I do hereby declare that the following is a full, clear, and exact description of the same, reference being had to the annexed 10 drawings, making a part of this specification, and to the letters and figures of reference marked thereon.

Figure 1 is a perspective view of a portion of a door and frame provided with my improvements. Fig. 2 is a bottom plan view of the same, and Fig. 3 is a section taken on the line *x x* of Fig. 2.

This invention has for its object to produce a simple, cheap, and durable weather-strip of few parts, and one that may be readily attached to any door, and not liable to get out of repair.

To this end the invention consists in the several details of construction, substantially 25 as shown in the drawings, and hereinafter described and claimed.

In the accompanying drawings, similar letters denote corresponding parts in all the figures.

30 My improvements are applicable to any door or shutter closing an opening, whether sliding or turning on a pivot; but to simplify matters they are shown in the present instance as applied to a door, A, of ordinary construction. Brackets B, attached to the door in any suitable manner, pivotally support the hinge-bar C, which is weighted at its rear end to gravitate between its pivotal connection and the door. A strip, D, is secured to the hinge-bar C by bolts E, passing therethrough and through flanges or extensions C', integrally cast with the hinge-bar. A strip, F, of rubber or metal, is adjustably secured between the bar C and hinge-extentions C' by the bolts E passing 40 through slots f, formed therein. The hinge at any suitable point is cut away, as at c, and is provided with a projection, c', to which is pivotally connected a trip-bar, G, slotted near its forward end, and held to place in a recess, a, 45 in the bottom of the door by a screw, H, pass-

ing through its slot. The free end of the trip-bar G is provided with an extension, g, so that when closing the door the extension, when brought against a stop, g', formed on the sill K, as shown in Fig. 3, will cause the strip F 55 to close tight against the sill. This stop g' is preferably formed by cutting away a portion of the sill; or any suitable stop may be provided, as found most practicable. A bracket or stop, H', attached to the frame of the door, 60 assists in forcing the strip close to the sill and holding the same there when the door is closed. The brackets B, which are secured to the door, are provided with flanges b, integral therewith, with their outer faces set at an incline in 65 conformity to the slant of the inclined portion of the overhanging plate or cap I, to which they are secured, thereby strengthening and bracing the same. These arms are cut away, as at b', to limit the upward movement of the outer 70 portion of the hinge carrying the strip D, which latter is likewise cut away, leaving a portion extending beyond to contact with the bracket. It will be seen that the plate D is secured to the hinge-bar C by the same bolts which serve to 75 adjust the strip F, thereby producing a more economical construction. It will be further noticed that the flanges or extensions c' of the hinge not only serve as a means for securing the strip thereto, but also as a means for bracing and strengthening the same, thereby permitting the use of comparatively light material.

In practice, the parts being adjusted as above described, the hinge-bar carrying the 85 strip, when the door is open, will assume the position shown in Fig. 3, and when the door is closed will occupy the position shown in Fig. 1 in consequence of the trip-bar contacting with the stop g' and the strip striking 90 against the stop-bracket H'.

Having thus fully described my invention, what I claim as new, and desire to secure by Letters Patent, is—

1. The combination of a weather-strip with 95 a weighted single hinge-bar having lateral extensions to brace said strip and serve as means for securing the two together.

2. The combination, with a door, of a weighted hinge-bar connected therewith and 100

carrying a weather-strip, of a trip-bar pivoted to said hinge-bar and slotted near its forward end, and a keeper passing through said slot to hold the trip-lever close to the under side of the door.

3. The combination of a weather-strip and its cap-plate with a bracket pivotally supporting said strip, and provided with lateral flanges having an inclined face to brace and strengthen said cap-plate, substantially as shown and described.

In testimony that I claim the above I have hereunto subscribed my name in the presence of two witnesses.

JOSEPH ^{his} X FISHER.
mark.
